UNITED STATES PATENT OFFICE.

LOUIS PRAT, OF PARIS, FRANCE.

INDUCED-DRAFT DEVICE.

Application filed June 3, 1920. Serial No. 386,378.

To all whom it may concern:

Be it known that I, LOUIS PRAT, citizen of the Republic of France, residing at Paris, France, 146 Avenue des Champs Elysees, 5 have invented certain new and useful Improvements in Induced-Draft Devices, of which the following is a specification.

My invention relates to an induced draft device of the type in which a fan draws a 10 portion only of the flue gases from the foot of the chimney and discharges it through a nozzle projecting inside the chimney, said nozzle operating as an ejector to carry along the remainder of the gases which rise directly 15 up the chimney. The object of my improvement is to enable an induced draft device of this type to always operate with maximum efficiency though the volume of the flue gases may vary, for instance when 20 the combustion increases or diminishes in the furnace producing said gases.

The fan employed in such devices is usually a centrifugal fan driven by an asynchronous electric motor which is adapted to 25 run only at substantially constant speed. But, so far as I am aware, in cases contemplated in my present invention, the only method used up to the present to meet the 30 variations of volume of the combustion gases is to provide, inside the chimney above the blowing nozzle, a damper adapted to restrict the gas passage when their volume decreases. It is well known however that, when the passage is thus restricted, 35 the efficiency of a centrifugal fan is considerably reduced, because a centrifugal fan, run at a given speed, possesses a satisfactory efficiency only for a given volume of gases delivered by it.

40 The present invention permits of dispensing with a damper while avoiding the loss of efficiency of the fan. According to the invention a plurality of centrifugal fans driven at a constant speed are provided, 45 each to deliver to the chimney a substantially constant volume of gases, and the number of fans in operation is varied as the total volume of gases to be delivered varies. Each fan is provided with a separate blowing 50 nozzle and the several nozzles are preferably arranged concentrically.

55 The accompanying drawings illustrate various embodiments of the invention in diagrammatic form. Figure 1 is a vertical section of a chimney stack provided with two fans having two concentric blowing nozzles,

and Figure 2 is a cross-section on line 2—2 of Figure 1; Figure 3 is a cross-section of a chimney with four concentric blowing nozzles; Figure 4 is a cross-section of a chimney with four nozzles, disposed around the central axis of the chimney and Figure 5 is a vertical section through one of the fans, shown diagrammatically in the preceding figures, illustrating also in elevation the electric motor driving such fan.

In Figures 1 and 2 two fans indicated by *h*, *j* are placed at the foot of a bi-conical chimney *e*, that is to say a chimney which is constricted at one part *u* and then widened out again above at *v*. Each fan is provided with an inlet *p* or *p*¹ open to the chimney so as to receive the combustion gases, and their blades *q*, such as are shown in the detail sectional view of Figure 5, 75 open into the stationary discharge spiral such as *r* which terminates in a delivery pipe *g* for fan *h* and *i* for fan *j*. These pipes terminate in concentric blowing nozzles *ab* and *cd* respectively, which open into the chimney substantially in the central axis of the latter. The two fans *h*, *j* may be of equal or of dissimilar capacity. They are each mounted on a shaft such as *s* (Figure 5), driven individually by an electric 85 motor *t* or other suitable means.

When the maximum volume of combustion gases is delivered from the furnace the two fans *h*, *j*, are run simultaneously; they draw in each a portion of the gases 90 through their inlets *p*, *p*¹ and force it out through nozzles *ab* and *cd*. The sectional area given each nozzle is that which affords the best efficiency for the given volume of gases delivered by each fan. The portion 95 of gases blown through *ab* and *cd* working as ejectors carry along the remainder of combustion gases which ascend directly up the chimney as shown by arrow *F* in Fig. 1.

When the volume of the combustion gases 100 diminishes, one of the fans is stopped and the other one which is still running then alone supplies gases to the circular central nozzle *ab*—assuming the fan to be *h*—or to the annular orifice comprised between *ab* 105 and *cd* in the case of fan *j*. Thus whichever fan remains in operation, it continues delivering substantially the same volume of gases through the same size orifice as formerly.

110 The method of working is the same in the device shown in Figure 3 in which four

fans h , h^1 , j , j^1 , are arranged to blow through four concentric nozzles k , l , m , n , respectively, the arrangement being the same as in Figures 1 and 2. One or more fans are set 5 in operation as the volume of combustion gases increases, and each fan always delivers substantially a constant volume of gases.

The blowing nozzles k , l , m , n , can also be arranged contiguous to each other around 10 the central axis of the chimney, as shown in the diagrammatic cross section of Figure 4. But the concentric arrangement is obviously preferable in order that the discharge from each fan may act with maximum efficiency 15 on the gases surrounding them in the chimney.

It will be obvious to any one skilled in the art that the invention as disclosed is not limited to forcing flue gases through 20 a chimney, but is applicable to any draft device in which any kind of gas is forcibly moved through a chimney.

I claim;—

1. In an induced draft device for chimneys or the like, a plurality of fans, each adapted to deliver a substantially constant volume of fluid into the chimney, and a permanently open discharge nozzle of predetermined size for each fan, disposed in 30 the chimney, to cause the fluid discharged by the fan to carry along the chimney gases in ejector fashion.

2. In an induced draft device, a biconical chimney, a plurality of centrifugal fans 35 each adapted to deliver a substantially constant volume of fluid into said chimney, the number of said fans in operation being proportional to the total volume of combustion gases in the chimney, and a permanently open discharge nozzle of predetermined size for each fan, and disposed in the 40 throat of said chimney, to cause the fluid

discharged by the fan to carry along the chimney gases in ejector fashion.

3. In an induced draft device, a biconical 45 chimney, a plurality of centrifugal fans each adapted to deliver a substantially constant volume of fluid into said chimney, the number of said fans in operation being proportional to the total volume of combustion 50 gases in the chimney, and a permanently open discharge nozzle of predetermined size for each fan, said nozzles being disposed in the chimney throat concentrically to each other and to the central axis of the 55 chimney, said nozzles adapted to cause the fluid discharged from them to carry along the chimney gases in ejector fashion.

4. In an induced draft device for chimneys or the like, a plurality of fans each 60 adapted to deliver a substantially constant volume of fluid into the chimney, and each adapted to operate independently of the others, and a permanently open discharge nozzle of predetermined size for each fan 65 disposed in the chimney to cause the fluid discharged by the fan to carry along the chimney gases in ejector fashion, the number of fans operating at a given time being proportioned to the total volume of 70 gases passing thru the chimney at that time.

5. In an induced draft device for chimneys or the like, a plurality of fans, each adapted to draw from and return into the chimney a substantially constant volume of 75 combustion gases, and each fan adapted to operate independently of the others, and a permanently open discharge nozzle of predetermined size for each fan and disposed in the chimney to cause the gases discharged 80 by the fan to carry along the remainder of the chimney gases in ejector fashion.

In testimony whereof I affix my signature,
LOUIS PRAT.
